ATTORNEY'S

UNITED STATES PATENT OFFICE.

WILLIAM B. FENN, OF PORT WASHINGTON, NEW YORK.

CORER.

Application filed April 8, 1922. Serial No. 550,643.

To all whom it may concern:

Be it known that I, WILLIAM B. FENN, a citizen of the United States, residing at Port Washington, county of Nassau, State of New York, have made a certain new and useful Invention in Corers, of which the following is a specification.

This invention is directed to corers, or, in other words, to a device for extracting the core from fruit such as apples; vegetables, such as tomatoes, etc.

The object of the invention is to provide a corer which is simple in construction, efficient in operation and economical of manufacture.

A further object of the invention is to provide corer edges opposite in action and mechanically operated.

Further objects of the invention will appear more fully hereinafter.

The invention consists substantially in the construction, combination, location and relative arrangement of parts, all as will be more fully hereinafter set forth, as shown in the accompanying drawings and finally pointed out in the appended claims.

Referring to the drawings:

Figure 1 is a top plan view of a corer embodying my invention, the jaws of the corer being open.

Fig. 2 is a similar view showing the jaws of the corer closed.

Fig. 3 is a sectional view taken on the line 3—3, Fig. 1, looking in the direction of the arrows.

Fig. 4 is a sectional view taken on the line 4—4, Fig. 2, looking in the direction of the arrows.

Fig. 5 is a view similar to Figs. 1 and 2 showing the jaws of the corer partially closed.

Fig. 6 is a sectional view taken on the line 6—6, Fig. 5, looking in the direction of the arrows.

Fig. 7 is a detail view in elevation of the corer jaws showing the same in open position.

Fig. 8 is an elevation showing a conveyor suitable for carrying and operating a plurality of my corers.

Fig. 9 is a plan view showing means for closing my corer.

Fig. 10 is a view in elevation of the corer showing the jaws closed, or the position assumed after having passed the closing detent shown in Fig. 9.

The same part is designated by the same reference character wherever it occurs throughout the several views.

While I have shown and will now describe my invention and mechanically actuated coring devices particularly adapted for use for extracting the cores from tomatoes, I do not desire to be limited or restricted in this respect as the features of the invention therein contained may readily be utilized for extracting cores from other vegetables, fruits, etc., and mechanical actuation thereof, while efficient, is not necessitated.

In the arrangement shown, however, I show a corer structure which is designed to be used in connection with a machine for removing the skins from tomatoes, and wherein the corer structure consists of a base 1 having secured thereto guide plates 2 which guide plates are secured in any suitable manner, for example, by means of screws 3. The guide plates are placed on opposite sides of the base 1; each of them is provided with one or more downwardly extending pins 4 which, in the form shown, are utilized to seat in sprocket chains 101 employed for moving the corer structure. Modifications in this detail, however, will readily occur to those skilled in the art without departing from the spirit and scope of my invention.

The base plate 1 is provided with a substantially circular orifice through the approximate center thereof, and secured to the plate 1 on opposite sides thereof, for example, by means of screws 5 is a pair of plates 6 and 7. (See Fig. 6). The lower plate 7 extends into the opening or orifice in the base plate 1 and is provided with a flange 8 which forms a pivotal support for the jaw 9 and members 9 and 10, which will be more fully hereinafter described.

The jaw members are each pivotally mounted on the respective flange portions 8 of the plates 7. The other plate 6 which is held clamped to plate 7 by the screw 5 is likewise provided with a flange portion 11 having an extending lip 12. The flange portion 7 and the lip 12 form a cutting annular recess between the lip 12 and the top of the base plate 1, it being understood that the plate 7 is countersunk relative to the base plate 1 at the edge of the orifice or opening through the center of the base plate 1. Held by the plate 6 with its flange and lip 11, 12, respectively, for rotary movement in the annular space above described, is

what I will term the actuating ring 13. This ring contains a projection in the form of a pawl illustrated at 14, which, when engaged, serves to rotate the ring in one direction, in the form shown counter clockwise, and substantially opposite thereto two rounded projections 15 and 16 which, when rotated, serve to rotate the ring in the opposite direction, in the form shown clockwise. The ring is also provided with two downwardly projecting lugs 17 and 18 arranged diametrically opposite each other, which lugs carry rigidly therewith pins 19 and 20. The jaws, as above noted, consist of substantially semi-cylindrical members 9 and 10, the upper ends thereof being cut away and the respective members being pivoted at the approximate end of their cut-away portion so that when the jaws are rocked so that the upper ends thereof move towards each other, the contacting edges form a straight line as illustrated in Fig. 2; whereas, the opposite ends thereof are at a maximum distance apart. When the jaws are in cutting contact with each other, i. e., the cut-away portions, it is understood that these portions are sharp-edged to form in effect clippers.

Each of the jaws 9 and 10 is provided with a cam groove 21. All of the jaws 9 and 10 are similarly constructed with the cam groove 21 extending in an upwardly direction throughout the width of the jaw, but it will be readily apparent that when two jaws are placed opposite each other the cam grooves 21 extend in opposed directions relative to each other. The pins 19 and 20 which form part of the rotatable ring 13 extend through the cam grooves 21 respectively of the jaw members 9 and 10 so that when the actuating ring is rotated in one direction, due to the cam action effect by the grooves 21 and the pins 19 and 20, the jaws are opened, and vice versa.

The corers may be mounted and operated in any convenient or suitable manner. As a practical illustration, however, I have elected to move a number of covers on a conveyor or chain 101, which is carried on pulleys 102 which are driven by power, as a motor (not shown). A frame or standard comprising uprights 103 and 103¹ and a bridging member 104 affords proper support for the conveyor. The pulleys may be provided with sprockets 105 for each side of the conveyor chain.

At a suitable position on the frame and bridge members I provide operating detents for closing and opening my corer. The closing detent finger 106 is carried on a fixture 107 for engaging lugs 15 and 16 as the corer passes the detent finger. This fixture may be secured to the bridge at any desired place where it is intended to close the corer and thus remove the core from the fruit 108 which is subjected to the operation by being

placed on the open corer as at a position, say X.

For opening the corer a detent similar to the closing detent is provided and this may likewise be placed at any desired position beyond a point Y where the fruit has been removed. Preferably, though not necessarily, I place the opening detent finger on the standard 103. As the corer passes this detent at a position, say M, the detent finger engages the opening lug 14 for rocking the actuating ring 13 to open the corer jaws 9 and 10.

The operation of the corer will now be briefly described. The corer is normally maintained in the position with the jaws open which convert the cutters or jaws into substantially a cylinder, in plan view, as seen in Fig. 1. The tomato or other article to be cored is impinged upon the jaws 9 and 10 so that the same encompass the core. It will be readily apparent that this will be facilitated when the edges of the jaws 9 and 10 are knife-edged, as above described. The corer assembly, in the form selected for illustration and which is being described, is then moved by the chain 101 which engages the pins 4, as described, until it is desired to cut out the core of the article, at which time the actuating ring 13 is rotated mechanically or otherwise by means of the lugs 15, 16 to the position shown in Figs. 2 and 4 whereby the core is cut out and allowed to drop through the open and extended bottoms of the jaw members 9 and 10. This operation does not, however, release the article impinged upon the jaw members 9 and 10 which is held thereto, the holes through side walls of the jaw members assisting to hold the article thereon. When it is desired to again open the jaws the lug 14 is mechanically or otherwise engaged to rotate the actuating ring in a counterclockwise direction back to the position shown in Fig. 1.

It might be advisable to remove the article being cored from the corer while the jaws are in a closed position, to ensure perfect extraction of the core.

Many modifications and changes in details will readily occur to those skilled in the art without departing from the spirit and scope of my invention as defined in the claims, but having now set forth the objects and nature of my invention and having shown and described a structure embodying the principles thereof, what I claim as new and useful and of my own invention, and desire to secure by Letters Patent is:

1. In a coring device comprising a pair of blades normally adapted to encompass a core and upon which the article to be cored is impinged, and means for moving said blades to sever the core from the article.

2. A coring device comprising a pair of substantially cylindrical blades normally adapted to encompass a core and upon which the article to be cored is impinged, and means for moving said blades to sever the core from the article. 70
3. In a coring device comprising a pair of blades normally adapted to encompass a core and upon which the article to be cored is impinged, and means for moving said blades to sever the core from the article at the top of said blades. 75
4. A coring device comprising a pair of substantially cylindrical blades normally adapted to encompass a core and upon which the article to be cored is impinged, and means for moving said blades to sever the core from the article at the top of said blades. 80
5. A coring device comprising a pair of blades normally positioned relative to each other to form a substantial cylinder in plan view, means for mounting said blades intermediate their ends for pivotal movement relative to each other, the tops of said blades being so formed as to contact with each other when said blades are pivotally moved, and means for moving said blades. 85
6. A coring device comprising a pair of blades normally positioned relative to each other to form a substantial cylinder in plan view, means for mounting said blades intermediate their ends for pivotal movement relative to each other, the tops of said blades above the pivotal support thereof being so formed as to contact with each other when said blades are pivotally rocked, and means for moving said blades. 90
7. A coring device comprising a pair of blades normally positioned relative to each other to form a substantial cylinder in plan view, means for supporting said blades, said blades being so formed that the top edges thereof may be made to contact with each other, and means for effecting a contact between the top edges of said blades. 95
8. A coring device comprising a pair of blades normally positioned relative to each other to form a substantial cylinder in plan view, means for supporting said blades, said blades being so formed that the top and side edges thereof above the support thereof may be made to contact with each other, and means for effecting a contact between the top edges of said blades. 105
9. A coring device comprising a supporting body having an orifice therein, coring blades located in said orifice, and means actuating said blades. 110
10. A coring device comprising a supporting body having an orifice therein, coring blades located in said orifice, and means carried by said body for actuating said blades. 115
11. A coring device comprising a supporting body having an orifice therein, and pro- 120
- vided with means for attachment to a carrier, coring blades located in said orifice, and means for actuating said blades. 125
12. A coring device comprising a supporting body having an orifice therein, and provided with means for attachment to a carrier, coring blades located in said orifice, and means carried by said body for actuating said blades. 70
13. A coring device comprising a supporting body having an orifice therein, coring blades located in said orifice, a movable member carried by said body, and means for actuating said blades by and in accordance with the movement of said member. 75
14. A coring device comprising a supporting body having an orifice therein, coring blades located in said orifice, a rotatable member carried by said body, and means for actuating said blades by and in accordance with the rotative movement of said member. 80
15. A coring device comprising a supporting body having an orifice therein, coring blades located in said orifice each provided with slots therethrough, a movable member carried by said body and provided with pins extending through said slots, said slots being inclined relative to the plane of movement of said member. 90
16. A coring device comprising a supporting body having an orifice therein, coring blades located in said orifice each provided with slots therethrough, a rotatable member carried by said body and provided with pins extending through said slots, said slots being inclined relative to the plane of movement of said rotatable member. 95
17. In a coring device a coring blade consisting of a substantially semi-cylindrical piece of metal in plan view with the top thereof substantially semi-circular in elevation view. 105
18. In a coring device a coring blade consisting of a substantially semi-cylindrical piece of metal in plan view with the top thereof substantially semi-circular in elevation view, and a slot in the body thereof extending at an incline to the horizontal axis thereof. 110
19. In a coring device a pair of coring blades of similar construction each comprising a substantially semi-cylindrical piece of metal in plan view with the top thereof substantially semi-circular in elevation view, the said blades being pivoted at the approximate ends of the curved top and opposed to each other to form a substantially cylindrical space between them. 115
20. In a coring device a pair of coring blades of similar construction each comprising a substantially semi-cylindrical piece of metal in plan view with the top thereof substantially semi-circular in elevation view, and a slot in the body thereof extending at an incline to the horizontal axis thereof, the 120
- 130

said blades being pivoted at the approximate ends of the curved top and opposed to each other to form a substantially cylindrical space between them.

- 5 21. In a coring device a coring blade consisting of a substantially semi-cylindrical piece of metal in plan view with the top thereof substantially semi-circular in ele-

vation view, and with a perforation through the side thereof, substantially as and for the purpose described.

In testimony whereof I have hereunto set my hand on this 6th day of April A. D., 1922.

WILLIAM B. FENN.
